Geo. F. Hayes

UNITED STATES PATENT OFFICE.

MICHAEL F. HAYES, OF NEW YORK, N. Y.

ERASER.

1,063,443.

Specification of Letters Patent.

Patented June 3, 1913.

Application filed April 15, 1912. Serial No. 690,716.

To all whom it may concern:

Be it known that I, MICHAEL F. HAYES, a citizen of the United States, residing in the borough of Manhattan, in the city, 5 county, and State of New York, have invented certain new and useful Improvements in Erasers, of which the following is a specification.

My improvements relate to the class of 10 abrasive erasers in which rubber is usually the main base or vehicle of the composition used for cleaning surfaces, as in the case of the so called "rubber" erasers furnished for the use of stenographers, typewriters and 15 draftsmen, and for clerical and analogous purposes.

The objects of the invention are, to render 20 an eraser of this class more effective and convenient in use; to protect it from unnecessary deterioration or contamination by reason of contact with the hand or extraneous substances; and to provide adequate means for sharpening it, and for cleaning its point by the removal of soil or smut imparted to the point or edge during use, as 25 after being employed in the removal of ink or substances which are apt to smudge.

The invention consists in the construction 30 and arrangement of parts herein described and claimed specifically, a distinguishing feature being the combination with the rigid metallic holder or handle for the eraser rubber of a rigid metallic attrition cap fitting, and rotatable on said holder in either 35 direction, and performing the double function of a protector for the eraser when the latter is not in actual use as such, and also of a cleaner for the rubber after use, as hereinafter fully set forth.

40 In the accompanying drawings, Figure 1, is a front end view of my improved eraser; Fig. 2, a central longitudinal sectional elevation taken upon plane of line 2—2 Fig. 1; Fig. 3, is a side elevation of the attrition cap and holder, when in the position shown in Fig. 2; Fig. 4, a side elevation of the "rubber" and holder removed from the attrition cap; Fig. 5, a central longitudinal sectional elevation showing a modification of the rubber holder; Fig. 6, is a section, much enlarged, of the outer end of the attrition cap; Fig. 7, a side elevation thereof, showing a corrugated structure; Fig. 8, a transverse section upon plane of line 7—7 Fig. 6.

55 It is to be understood that by the term "rubber" I herein designate any suitable or

well known compound adapted to purposes of erasion, including the various compositions of rubber and other ingredients known in the art.

The rubber R, consists of a cylindrical stick or body portion having a conoidal outer end r, preferably in the form of a paraboloid, as shown in the drawings, which is the best form for practical purposes, 60 although any tapering configuration circular in cross section will come within the spirit and intent of my invention, which contemplates in this respect a shape that may be attained by the rotation of the attrition cap A, in either direction upon the tubular holder H, over which the attrition cap fits snugly.

The attrition cap A consists of a rigid tube the outer extremity of which is formed 75 with a concavity a, having an attritive surface adapted to grind or abrade the end r, of the rubber R, when rotated in contact therewith. This abrasive surface a', may obviously be formed by many well known 80 expedients, as by roughening by mechanical means, but I prefer to line it with an abrasive compound which in hardening becomes practically an integral part of the cap. I have found a composition containing com- 85 minuted emery effective for the purpose,—since the amount of material to be removed from the end r, of the rubber R, in order to clean and sharpen it is comparatively slight under ordinary conditions of use. In 90 order to secure the perfect adhesion of the abrasive lining internally, and to afford purchase for the fingers of the user externally, the attrition cap A, may be corrugated longitudinally as indicated in Figs. 7 and 8. 95

The rubber R, is provided with a rigid tubular holder or handle H, fitting snugly over and contacting with the cylindrical body thereof, and affording means whereby the rubber may be manipulated in use without fingering the same directly,—it being well known that rubbers of this character are more or less absorbent, and deteriorate if contaminated. The body of the rigid tube of which the attrition cap A, is formed, 100 fits snugly over the rigid tubular holder H, so as to be sustained in perfect alinement therewith, while rotatable thereon in either direction. Hence, in cleaning the conoidal end r, of the rubber R, the attrition cap A, 105 or the holder H, either or both, may be rotated in either direction, or alternately in

opposite directions, as may be found most expedient or convenient. Furthermore, the attrition cap A, and the holder H, are slideable telescopically one upon the other, so that full and unrestricted pressure can be exerted upon the conoidal end of the rubber as the latter is worn away. Hence, also owing to the perfect alinement maintained between the parts, the rubber tip if properly cleaned is always perfect in configuration and therefore adapted to all requirements of use.

In the modification shown in Fig. 5, the holder H, is formed with an outer casing 15 h, fitting over the inner end of the attrition cap A. Either the attrition cap A, or the holder H, may be provided with an angular flange f, to prevent the device rolling on a smooth surface.

20 The elasticity and resiliency of the rubber R, admits of its adjustment within the holder H, to compensate for wear, &c., and the adjustment of the attrition cap A, on the holder also contributes to the utilization 25 of practically the whole length of the rubber R.

The use of the attrition cap A, is obvious. When the rubber R, is not desired for actual use it is protected by the cap A, against 30 contact with extraneous objects. To remove any smudge or dirt from the end r, of the rubber R, the cap A, is pressed slightly against it, and turned in either direction, thereby abrading the end r, and cleaning it 35 with a minimum of waste, at the same time restoring and perfecting its shape so that it is in best condition for future use. This may be conveniently accomplished by alternately reversing the motion after a partial 40 turn of the attrition cap A, or of the holder H, in either direction,—the complete rotation of either part not being necessary. To remove the dust from the attrition cap 45 the latter is withdrawn temporarily from the holder H after the grinding operation, and tapped gently; or the dust may be dis-

lodged by blowing through an axial hole a², formed for the purpose in the extremity of the cone.

For convenience of identification in the 50 claims I have therein designated the end r, of the rubber R, as the tip thereof.

The conoidal tip r, of my improved form of rubber adapts it for use in small areas, and for purposes of erasure where the work 55 is close and intricate, without danger of disturbing or defacing adjacent lines or marks, thereby restricting the necessity for retouching or remarking within prescribed or desired limits, and hence broadening and enlarging the functional scope of the eraser, 60 and obviating superfluous labor.

What I claim as my invention and desire to secure by Letters Patent is,

1. An eraser of the character designated, 65 comprising a rigid tubular holder, a conoidally tipped eraser formed with a cylindrical portion which fits snugly within said rigid tubular holder, and a rigid attrition cap formed with a cylindrical portion fitting 70 snugly over, and slideable and rotatable in either direction upon, said rigid tubular holder, said cap being also formed with an internal concave abrasive surface adapted to contact with the conoidal tip of the 75 eraser, for the purpose set forth.

2. An eraser of the character designated, comprising a rigid tubular holder, a conoidally tipped eraser formed with a cylindrical portion which fits snugly within said 80 rigid tubular holder, and a longitudinally corrugated rigid attrition cap fitting snugly over, and slideable and rotatable in either direction upon, said rigid tubular holder, said attrition cap being also formed with 85 an internal concave abrasive surface adapted to contact with the conoidal tip of the eraser, as and for the purpose set forth.

MICHAEL F. HAYES.
